CLAIM

The ornamental design for a video game pistol holder, as shown and described.

DESCRIPTION

FIG. 1 is a perspective view of a video game pistol holder showing my new design;

FIG. 2 is a front end elevational view thereof;

FIG. 3 is a rear end elevational view thereof;

FIG. 4 is a right side elevational view thereof, the left side elevational view being a mirror image thereof;

FIG. 5 is a top plan view thereof;

FIG. 6 is a bottom plan view thereof; and,

FIG. 7 is a sectional view taken along line 7—7 of FIG. 1, partially cutaway for the sake of convenience.

FIG. 2.

FIG. 3.

FIG. 6.
